METHOD OF FORMING ROD-LIKE PAPER ARTICLES

John V. Atanasoff, Fulton, Md., assignor to Communications Research, Inc., Clarksville, Md., a corporation of Maryland

Application August 27, 1951, Serial No. 243,858

8 Claims. (Cl. 93—1)

This invention relates to a rod-like member or article fabricated of paper and particularly to an article of this type which may be utilized in the confectionery art in the same manner that the well-known wooden confectionery "stick" is employed, one end portion thereof to comprise a support or core upon which a body of ice cream, candy or other confection may be mounted and the remaining portion to constitute a handle by means of which such confectionery body may be manipulated while being consumed. The invention also contemplates the provision of a novel method or process by which such rod-like paper members or sticks may be quickly and economically produced in quantity and in a continuous manner.

The improved paper stick is not only less costly to manufacture than those fabricated of wood and which have heretofore been so widely used, but also possesses a number of advantages which render it decidedly superior in actual use to the heretofore commonly employed wooden stick. While it is formed in such a way that it has the mechanical strength which a confectionery stick should have in order to accomplish its intended functions in a satisfactory manner, it does not have such strength as a column that it can injure the mouth of a child who falls to the ground while eating the confectionery which the stick supports. Accidents of this nature rather frequently occur and, where the well known wooden stick is in the child's mouth, may be of serious character, being rendered especially so by reason of the fact that the grain of the wooden stick runs generally longitudinally of that stick so that the stick may split longitudinally and a sharply pointed portion result which may well be able to penetrate deeply into the roof of the mouth if sufficient pressure is applied.

The improved paper stick contemplated by the invention can be formed in such manner as to be relatively large in transverse section for a given amount of paper employed in its manufacture and the preferred form of the invention contemplates the fabrication of one portion of the paper web from which the stick is formed into a cellular core, the remainder of the paper web being wound about this core to form a tubular enclosure therefor. By forming as a preliminary step a cellular core comprising a number of relatively folded panels of the paper web from which the stick is made, and thereafter winding about this pre-formed core a sufficient amount of paper in sheet form to closely support the core and cause it to have the necessary stiffness as a column, a very satisfactory low-cost stick may be made, such stick having any desired shape but being preferably rectangular in cross section and of the same overall outside dimensions as the wooden stick heretofore so widely utilized in the confectionery trade.

Adhesives of various kinds may be employed to secure the various panels of the stick to each other so as to form a rigid structure. Thermosetting or thermoplastic materials may be employed in lieu of ordinary adhesives to provide greater strength if desired and adhesives of water-proof nature may be employed to increase the resistance of the resultant stick to the weakening effect of moisture.

A novel method of forming the stick is utilized, this method being of continuous character and contemplating the advancement of a web of paper along a fixed path at a desired rate, the web being acted upon at each of a successive series of stations along its path of movement and all of the stick forming operations being accomplished as the web successively passes these stations, the com-

2

pleted stick issuing as a continuously advancing member after the last operation has been accomplished and, after having been subjected to any desired final compacting or shaping operations, is transversely sheared into units of predetermined length. Where the paper sheet is of thermoplastic or thermosetting nature, or an adhesive of thermoplastic or thermosetting character has been applied thereto, heating elements may be positioned along the path of movement of the web to supply the heat necessary to bring about softening or setting of the heat responsive materials and, if necessary or desired, a cooling instrumentality may be utilized to quickly cool the thermoplastic or thermosetting material after it has been heated. Suitable means for the accomplishment of the method may be employed and this means may obviously be varied in character in accordance with the nature of the paper web to be acted upon, the nature of the adhesive to be employed and the design of the stick to be produced, particularly its cross sectional shape and dimension.

The method may be said to comprise a series of steps some of which are repeated a number of times in the fabrication of the stick but in every instance the initial operation will comprise acting upon the advancing paper web to form the cellular core about which the remainder of the web is ultimately wrapped. The cellular core is, as previously explained, formed in a continuous manner by means which acts upon the advancing strip so as to form a plurality of narrow, longitudinally extending interconnected panels. These panels are then relatively folded to form the core, which is preferably of "zig-zag" cross section. The means for forming the panels and folding them may include devices for scoring or creasing the paper along parallel lines as a preliminary operation, followed by means for performing the folding operations, or the creasing and panel folding operations may be performed simultaneously and be in the nature of a crimping procedure.

At or about the time that a portion or band of the advancing web is acted upon to form the cellular core the web is creased longitudinally, also in a continuous manner, closely adjacent the inner terminal panel of the core and along parallel lines to facilitate folding over of the cellular core onto the adjacent portion of the web and to define an elongated panel which may be designated an edge panel. Following the formation of the cellular core and the adjacent edge panel, the advancing web passes an applicator for an adhesive of suitable character which applies adhesive to one surface of the edge panel and to the surface of an adjacent strip the width of which, when added to the width of the edge panel, comprises a strip coextensive in width with that of the cellular core.

The operation of folding over onto the adhesive coated surface of the web the previously formed cellular core is accomplished by stationary means positioned adjacent the path of travel of the web. Such a means may include a stationary cam which is engaged by the advancing core and which turns the core gradually about that edge thereof which is connected to the previously formed edge panel, through an angle of 180°, thus bringing the core into full contact with the previously coated band of the web, the edge panel which connects the core and web being moved into right-angular relation to the web during this operation. The folding operation may conveniently be performed in part prior to the time of the application of adhesive to the web but in any event the adhesive is applied prior to the completion of the folding operation described.

The cellular core and the underlying band of the web with which it has been brought into engagement then passes between rollers which further establishes firm contact between core and web and simultaneously forms two further parallel creases in the web, the first of these being immediately adjacent the folded over core, a second narrow band or panel being thus formed, which panel is to constitute the second edge panel of the stick after a further folding operation has been accomplished. Following the emergence of the structure thus formed from the roll pass adhesive is applied to the band of the oncoming paper web immediately adjacent the folded over core, this adhesive covering the face of the newly formed

edge panel and an adjacent width of the web which is coextensive with the core, the application of the adhesive at this station proceeding also in a continuous manner.

At a further station that edge of the traveling web which includes the folded over core encounters a folding means which effects the gradual folding over through 180° of the previously formed rib-like structure comprising the core and the band or side panel to which one side of the core has been adhesively secured, the second edge panel being simultaneously brought into position. At this point there has been completed a rod-like member comprising a cellular core and four enclosing panels, two side panels which may be relatively wide, and two edge panels which are preferably quite narrow, the core thus being completely enclosed. Such a member if severed into lengths might be of utility for certain purposes but where a stick to be used in the confectionery trade is the ultimate article desired, and the web is of relatively thin paper, it is important to continue the procedure, which is in the nature of a winding operation, until the core is enclosed within a tubular structure each wall of which is several plies in thickness. Therefore the web is made sufficiently wide initially to provide the necessary material for the formation of a tubular envelope of the desired number of thicknesses and the operation of turning over the first formed tubular core is continued until the web is completely consumed.

At the conclusion of the folding operation the resultant advancing stick may be acted upon by rollers which further define its shape in transverse section and compact its structure, these further rolling operations being especially desirable under some circumstances, finally it is sheared to length, its ends being rounded or cut square as desired. The operations described can be performed quite rapidly and the output of a single machine constructed to accomplish the method will be very great per unit of time. The cost of production is extremely low and the resultant article, while being in all respects eminently suited for the intended purpose, much less costly than the wooden stick heretofore so widely employed, as well as having the enumerated advantages.

In the accompanying drawings elements of a machine or apparatus for acting upon a moving paper web in the specified manner are illustrated and, by means of diagrams, the various steps of the method are indicated. It will be understood that the method may be varied in certain respects in order to accomplish the manufacture of rod-like paper articles which are intended to be put to uses other than as confectionery sticks and that sticks having cross sections which are not rectangular may be produced by slightly varying the means employed and slightly modifying the steps of the method, both method and article being subject to modification without departure from the invention.

In the drawings:

Figure 1 is a perspective view of a rod-like article intended for use as a confectionery stick, produced by following the novel method;

Figure 2 is a section on line 2—2 of Figure 1, being a transverse section through the stick but on a larger scale and with panels spaced apart so that they may be individually perceived;

Figure 3 is in the nature of a diagram indicating a paper web and the successive operations performed upon that web in order to accomplish the manufacture of the stick;

Figure 4 is a second diagram intended to further illustrate the nature of the operations performed on the web, station by station;

Figure 5 is a plan view showing a portion of the moving paper web and several of the stationary instrumentalities which act upon it, including means for forming the cellular core, applying adhesive, and folding over the core thus formed;

Figure 6 shows in side elevation the web and elements illustrated in Figure 5;

Figure 7 is a section on line 7—7 of Figure 5;

Figure 8 is a section on line 8—8 of Figure 5;

Figures 9, 10 and 11 are sections on lines 9—9, 10—10 and 11—11, respectively, of Figure 5;

Figure 12 is a section on line 12—12 of Figure 5;

Figure 13 is a similar section taken at a subsequent station along the length of the web, for instance a section along the line 13—13 of Figure 16;

Figure 14 is a perspective view of portion of an apparatus for finally compacting and shaping the issuing stick prior to its severance into short lengths;

Figure 15 is a section on line 15—15 of Figure 14; and

Figure 16 is a side elevation of the shaping and compacting devices of Figures 14 and 15 together with certain of the means for accomplishing the final turning operations.

The web of paper from which the stick is formed in a continuous manner is indicated at 10 and, while the elements of the machine for performing the method may be considerably varied in position and character, it is preferred that the web shall move along a horizontal path in the direction of arrow P (Figure 4) and that suitable means be provided for positively advancing this web at a uniform rate and for preventing it from deviating laterally from the desired path of advancement. The upper roller of a cooperating pair of driven paper engaging and advancing rollers is indicated at R in Figure 5, and there may be a number of such pairs of rollers. The normal width of the oncoming web is that which may be observed at station A in Figure 3. At station B one margin of the web passes between parallel rollers 11 and 12, the nature of which may be most clearly observed in Figure 7, and this margin is acted upon by the cooperating sharply grooved portions 11' and 12' of the rollers in such manner as to form a serpentine or crimped section which includes a number of panels, for instance ten as shown in Figure 7, adjacent panels being angularly disposed relatively to each other and alternate panels approximately parallel, the panels being of approximately the same width, this being the first operation performed in the fabrication of the cellular core unless, by reason of the nature of the paper, it is desirable to previously score the web along parallel lines so as to form lines or creases to facilitate the subsequent relative folding of the panels.

Simultaneously with the operation accomplished by the rollers 11 and 12 in the forming of the core panels, which are given the reference numeral 14, two crease or fold lines are formed immediately adjacent the innermost core panel 14, these creases being indicated in dotted lines at 15 and 16 in Figure 3 and in Figures 7 to 12 inclusive, the scorings or fold lines 15 and 16 being formed by the cooperation of circular ridges 17 and 18 on roller 12 which enter correspondingly shaped grooves formed in roller 11. The narrow band of paper between creases 15 and 16 ultimately becomes one of the edge panels immediately adjacent the cellular core, and which panel is indicated at 19.

In the average case it will be found to be undesirable to form the cellular core at one operation, which may be too drastic for the quality of the paper undergoing fabrication, and formation of the serpentine core may therefore be accomplished at two or more stations, the operation at station B being the initial operation and the operation being completed, in the form of the invention selected by way of example, by the rollers at station C, shown in Figure 8 of the drawings. It will be observed from an inspection of Figure 5 that the roll pass at station C narrows the core and increases its depth, the ridges and grooves of the rollers 20 and 21 at this station being narrower and deeper than those at the preceding station, likewise the narrow band 19, which is to form the initial edge panel, is curved to a smaller radius and the creases emphasized, the circular edges 23 and 24 of the roller 21 being somewhat larger in diameter than the corresponding ridges 17 and 18 of roller 12 and being slightly closer together. The margin of the web which has thus been acted upon at stations B and C is a zig-zag structure comprising ten relatively folded panels and, as the web continues to advance, this structure or cellular core is repeatedly turned or folded over toward and onto the flat portion of the web, being thus continuously wound into the remainder of the web. The initial winding operation must, of course, be performed in such manner that the panels will not be straightened out and the cellular aspect of the core lost either wholly or in part and to obtain this objective the core is caused to enter a tubular cam member indicated at 30 with elongated interior blades or ridges 31 which follow the curvature of the cam and serve to maintain the angularity of the panels and the integrity of the core as it passes through the tubular cam.

In Figures 9, 10 and 11 of the drawings the traveling core is shown in three successive positions as it is turned through an angle of 180° about its inner edge toward

and into contact with the upper surface of the traveling web 10 and it will be observed from these three figures of the drawings that, as the core structure is overturned the edge panel 19 straightens out until finally, when the core structure has been turned through 180° and is in contact with the upper surface of the web the panel 19 is disposed at a right angle to the web, as shown in Figure 12 and at station D in Figure 4. Prior to contact of the overturned core with the web against the immediately adjacent mutually facing margin of the flat web an adhesive of suitable character is applied to such margin by any appropriate means.

There is shown in Figure 5 of the drawings an adhesive applicator 33, which may be a roller continuously supplied with adhesive in a suitable manner. Thus the 15 ridges of the core are brought into contact with the previously coated area of the web as the core enters the pass between rollers 34 and 35 of Figure 12 and, in passing through are pressed tightly against the web, the lower roller 34 having a cylindrical end portion 34a which supports the flat band of the web and the upper roller 35 having the grooved portion 35a which bears down upon the core, maintains the integrity of the core, and presses the peaks of the ribs of the core closely against the adhesive coated surface of the web. At the same time, and due to the cooperative action of circular creasing edges 37 and 38 formed on roller 35, and corresponding grooves formed in roller 34, a further edge panel is defined by 25 parallel creases, thus facilitating the operation of again overturning the core with attached panel portion and bringing about the formation of a stick of truly rectangular cross section.

Similar operations are performed at the stations which follow, i. e. stations E, F, G, H and I, which are indicated in Figure 3 of the drawings, adhesive being applied prior to the completion of the folding operation in each instance, a further edge panel being defined by parallel creases, and light pressure being applied to the freshly folded over partially completed stick, each subsequent pair of rollers, of which examples are indicated at 40 and 41 in Figure 13, being provided with a web supporting cylindrical end 40a, a stick engaging cylindrical end 41a of reduced diameter, annular ridges 42 and 43 formed on roller 41 being adapted to enter grooves 44 and 45 of roller 40 in further creasing and defining an edge panel. It will be appreciated that as the overall dimensions of 45 the stick increase due to the winding operation the edge panels must be of increasing width and this is accomplished by more widely spacing the scoring edges 42 and 43 of roller 41 as the terminal station is approached.

In Figure 4 the several overturning operations performed are indicated diagrammatically and from an inspection of this figure the nature of the winding operation will be more fully appreciated. It is, of course, necessary to space the stations apart from each other a distance which will permit the folding operation between stations to be accomplished without over-stressing and possibly rupturing the paper. For instance, one margin of the core, in passing through the cam 30, will move along a path which is longer than the opposite margin and unless the cam 30 is of sufficient length this margin, which is, of course, the outer margin, might be over-stretched and broken. Hence the several core overturning cams must be of a length which is found suitable, having in mind the nature of the paper which is being fabricated. For paper of firm quality the distance between stations should be not less than approximately 10 inches when paper sticks approximately three-eighths inch in width are being fabricated. For paper which is more stretchable the distance between stations may be less, and one skilled in the art would readily appreciate the fact that a machine may be readily devised which will accomplish the desired function without overstraining and weakening any portion of the paper in the process of forming the stick.

The stick will have been fully wound when it issues from between the two cooperating rollers at station K but it may be desirable to pass it between final shaping and compacting devices before cutting it into lengths, particularly if the adhesive has not hardened. Three roll passes are indicated, respectively, at stations L, M, and N, Figure 16. As shown in Figures 14 and 15 the cooperating rollers 50 and 51 and 52 and 53 at stations L and N, respectively, have reduced central cylindrical portions which bear upon the upper and lower surfaces of

the stick and cylindrical end portions which have peripheral contact with each other, for roller spacing purposes, and annular inner surfaces which engage the edge panels of the stick. Intermediate stations L and N, two edge panel engaging rollers 55 and 56 may be positioned with advantage. Other arrangements of stick sizing and finishing instrumentalities may be employed, those shown being illustrated by way of example.

As will be clear also, to one skilled in the art, the improved stick or rod-like article may be fabricated with the aid of means which is specifically different from that shown but which is nevertheless capable of accomplishing the several steps of the method and producing the desired article.

Having thus described the invention, what is claimed as new and desired to be secured by Letters Patent is:

1. The method of forming a rod-like paper article which comprises advancing an elongated web of sheet material in the direction of its length, acting upon a lateral portion of the advancing web to form said portion into a plurality of narrow longitudinally extending adjacent panels, manipulating said panels to form a cellular core, and relatively rotating core and web as the web advances, to enclose the core in the remainder of the web.

2. The method of forming a rod-like paper article which comprises advancing an elongated web of sheet material in the direction of its length, acting upon a lateral portion of the advancing web to form said portion into a plurality of interconnected narrow, longitudinally extending and relatively foldable panels, relatively folding said panels to form a cellular core and enclosing the core in the remainder of the web by relatively rotating the core and the remainder of the web.

3. The method of forming a rod-like paper article which comprises advancing an elongated web of sheet material in the direction of its length, acting upon a lateral portion of the advancing web to form said portion into a core comprising a plurality of longitudinally extending narrow, interconnected, angularly disposed panels of approximately equal width, and closely enveloping said core, while maintaining it constant in cross section, in the remainder of the web.

4. The method of forming a rod-like paper article which comprises advancing an elongated web of sheet material in the direction of its length, continuously acting upon one lateral portion thereof to form a cellular core of zig-zag formation, and winding said core into the remainder of the sheet.

5. The method of forming a rod-like paper article which comprises advancing an elongated paper web in the direction of its length, acting upon a lateral margin thereof as it passes a core forming station to continuously form a core of zig-zag formation, gradually rotating the core as the web further advances to bring the same into contact with the web, and thereafter continuing the rotation of core and that portion of the web which is in contact with the core until the core is enclosed in a multi-ply covering.

6. The method of forming a rod-like paper article which comprises advancing an elongated paper web in the direction of its length, acting upon a lateral margin thereof as it passes a core forming station to continuously form a core of substantially rectangular cross section and an adjacent panel the width of which is equal to the thickness of the core, and gradually turning the core angularly as it advances with the web to bring the side of the core into contact with the web and the panel into angular relation to the web.

7. The method of forming a rod-like paper article which comprises advancing an elongated paper web in the direction of its length, acting upon a lateral margin thereof as it passes a core forming station to continuously form a core of substantially rectangular cross section and an adjacent panel the width of which is equal to the thickness of the core, applying an adhesive to the surface of said panel and an adjacent band of the web coextensive in width with the web, and gradually turning the core angularly as it advances with the web to bring the side of the core into contact with the web and the panel into angular relation to the web.

8. The method of forming a rod-like paper article which comprises advancing an elongated paper web in the direction of its length, forming in a lateral marginal portion of the web and relatively folding a plurality of elongated interconnected panels in a continuous manner as

the web advances, to form a core, and thereafter repeatedly rotating the core about axes parallel to the direction of movement of the web, respectively, as the web and core advance, to wind the web wholly about the core.
